(57) **CLAIM**

The ornamental design for a digital camera, as shown and described.

DESCRIPTION

FIG. 1 is a top, front and right side perspective view of a digital camera showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof;

FIG. 7 is bottom plan view thereof;

FIG. 8 is a left side elevational view of the digital camera of FIG. 1, showing the display panel in an open position and rotated 90°; and,

FIG. 9 is a left side elevational view of the digital camera of FIG. 1, showing the display panel in an open position and rotated 135°.

The portions of the digital camera in broken lines in all figures are shown for illustrative purposes only and form no part of the claimed design. The directional arrow in FIGS. 8 and 9 indicates the direction of the movement of the claimed design in operation and forms no part of the claimed design.
